[57] CLAIM

The ornamental design for a machine for pressure testing truck tires, as shown and described.

DESCRIPTION

FIG. 1 is a perspective view of a machine for pressure testing truck tires showing my new design;

FIG. 2 is an enlarged front elevational view thereof;
FIG. 3 is an enlarged right side elevational view
thereof;

FIG. 4 is an enlarged rear elevational view thereof;

FIG. 5 is an enlarged top plan view thereof, the bottom
being flat and unornamented.
